G. C. Manner,

Piano.

No. 97,943.

Patented Dec. 14, 1869.

United States Patent Office.

GEORGE C. MANNER, OF NEW YORK, N. Y.

Letters Patent No. 97,943, dated December 14, 1869.

IMPROVEMENT IN UPRIGHT PIANOS.

The Schedule referred to in these Letters Patent and making part of the same.

To all whom it may concern:

Be it known that I, GEORGE C. MANNER, of the city, county, and State of New York, have invented a new and useful Improvement in Upright Pianos; and I do hereby declare that the following is a full, clear, and exact description of the construction and operation of the same, reference being had to the accompanying drawings, making a part of this specification, in which the figure is a longitudinal vertical section.

This invention consists in placing the end of the supporting-beams that extend from the bottom to the top of upright-piano frames, at points between the front and rear sides of the top piece, and between the front and rear sides of the bottom piece, instead of at the rear sides of such pieces, as heretofore, for the purpose of enabling the said beams to render a better support to the top piece against the strain of the strings.

Also, in connecting the sounding-board with an iron enclosing-frame, so shaped that the sounding-board shall receive a bellying form toward the strings, when the screws which confine them to the frame are driven home.

In the drawings—

A is the top or rest-piece; A' A', the side pieces; and A", the bottom piece of the supporting-frame of an upright piano.

B are the inclined strings.

Ordinarily, the strings of upright pianos are stretched perpendicularly. The disadvantage of this position is that the pivot of the hammer-handle C cannot be located so near the strings as to necessitate the falling back of the hammer-head C' after each blow, and, at the same time, give sufficient room for the "action" C". But, by stretching the strings in an inclined position, the "action" may be located at a point which shall give it all necessary room, and which shall also be out of the vertical plane in which lies the point of contact between the hammer-head and strings. This location compels the hammer to fall back, after every blow, by its own weight. It also enables the stop that limits the backward fall of the hammer to be placed at a point whence the hammer, on rising, gains enough momentum to deliver a blow of the requisite force.

D are supporting-beams, placed between the top and bottom pieces A A'.

Usually, the supporting-beams of upright pianos are vertical, like the strings, and are located at the extreme rear side of the frame. As their function is to sustain the frame against the strain of the strings, it is obvious that such a location prevents them from

discharging this function to the best advantage, inasmuch as the strain has in its favor the leverage of the entire width of the top and bottom pieces.

My plan is to place the ends of the beams in lines midway, or otherwise, of the width of the top and bottom pieces, and to pass vertical stay-rods D' between the rear sides of such pieces, such stay-rods having screws and nuts at their ends. In this way, the leverage that before was all in favor of the strain, is now turned against it, by so much as the ends of the beams are brought nearer the front sides of the top and bottom pieces, where they serve as fulcrum, the power being applied by the strings, and the resistance being supplied by the stay-rods.

E shows an iron frame, sustaining the plate to which the lower ends of the strings are attached, and provided with arms e' e", projecting horizontally rearward from top and bottom, between which arms the supporting-beams are placed, the upper ones, e, sustaining the top piece A, and the lower ones, e', resting on the bottom piece A". The frame and its arms are all cast in one piece.

The frame completely encloses the sounding-board E' in a rabbet, e", that face of the rabbet on which the sounding-board rests being concave transversely, so that when the sounding-board is screwed down into the rabbet, it shall take a bellying form toward the strings, in the same manner and upon the same principle as a violin, so as to allow for expansion and contraction, and favorably affect the tone of the instrument.

The sounding-board being affixed by screws to its frame, may be easily taken off at any time.

Packing, h, of any suitable material, is placed between the sounding-board and the faces of the rabbet, so as to prevent the frame from rattling.

Having thus described my invention,

What I claim as new, and desire to secure by Letters Patent, is—

1. The supporting-beams D, when placed so that their ends occupy points between the front and rear sides of the top and bottom pieces, substantially as and for the object explained.

2. The frame E, provided with the concave rabbet e", for the purpose of giving the sounding-board a bellying form, substantially as and for the object specified.

G. C. MANNER.
